UNITED STATES PATENT OFFICE

2,155,895

AUTOMATIC FEEDING DEVICE

George A. Gibson, Jr., New York, N. Y.

Application June 30, 1934, Serial No. 733,257

19 Claims. (Cl. 271—52)

The object of this invention is to provide a very efficient automatic feeding device for feeding paper, cards, envelopes, folders, bags, etc., and, while not limited thereto, it is well adapted for use with a rotary printing machine of the type known as the multigraph.

My device is of the type in which the blanks are fanned or combed and delivered by gravity or other means to a friction feeding roller the separation being accomplished by a second friction member adjusted to bear against or nearly against the friction feeding roller.

By experiment, I have found that when a gravity magazine such as the one I employ is loaded, the inherent qualities of the blanks being fed, such as length, stiffness, thickness, curvature, etc., determine to a great extent the angle at which the leading blank of a lift will naturally be presented to the feeding roller, other means of controlling this angle being absent. In my invention I recognize this "natural" tendency as the controlling factor, and provide means of maintaining this angle of the leading blank to a great extent against change caused by variation of other factors, such as, angle or slope of the gravity magazine, quantity in the magazine, amount of degree of fanning or combing,—factors which would in many cases require great care and constant attention on the part of the operator.

By experiment, I have also found that to obtain the most positive pick-up of the feeding roller, the direction naturally assumed by the blank as it is first acted upon by the feeding roller should be maintained as nearly as possible until the leading edge has passed between the feeding roller and separating member; the flexing of the blank should be as little and as gradual as possible particularly until this part of the feeding operation has been completed; the angle formed by the blank and the separating member at the first point of contact of the blank with the separating member should be as small as possible. The reverse of these conditions causes resistance to the movement of the blank being fed, and consequent slipping of the feeding roller.

Objects of my invention are, therefore, to provide means for maintaining the leading blank in its normal or natural direction according to its inherent qualities, to provide means for setting the separating member in appropriate angular relationship with this normal or natural direction, to provide means for flexing the blank gradually and uniformly, to provide means for hold-

ing and adjusting the separating member towards and from the feeding member, also, and particularly, to provide means of accomplishing these ends for blanks of different length, width, thickness, stiffness, curvature, etc., and in various lateral positions.

A further object is to provide an adjustable feeding belt to co-operate with the feeding roller and other adjustable members to secure positive feeding.

A further object is to provide adjustable means for preventing the packing down of heavy or short bulky blanks against the feeding roller and feeding belt, a condition which would otherwise interfere with the positive pick-up of these feeding members.

A further object is to provide an inclined removable hopper easily adjustable to different angles to insure proper contact of the blanks with the feeding members, pivoted near its upper end to cooperate with other means provided to secure proper angular relationship of the leading blank with the separating member, adjustable in itself for width of blanks being fed, and slideable laterally as a unit upon its supporting structure for positioning with relation to the printing or other machine.

A further object is to provide ratchet mechanism permitting pull-out rollers to complete the operation of withdrawing the blank from between the feed roller and separating member.

A further object is to provide convenient means for changing the effective length of the feed stroke, this feature being of particular value in the feeding of short blanks.

A further object is to provide convenient means for cutting off the feeding altogether, which is useful when the printing or other machine is idling for inking up, etc.

A further object is to provide a feeding device of simple knock-down construction, one which may be quickly set for different kinds of blanks, and for correct position and timing with reference to the printing or other machine.

A further object is to provide a blank holding and separating unit removably mounted, and a delivery or registering unit slidably and removably mounted upon a base frame.

A further object is to provide a base frame upon which different types of magazine and separator units may be removably and interchangeably mounted, and upon which different types of delivery or registering units may be removably, slidably and interchangeably mounted.

A further object is to provide a delivery or

55

registering unit removably and slidably mounted, and adapted to be driven by and from the shaft underneath the power drive base of the multigraph.

5 A further object is to provide means for varying the speed at which blanks may be delivered to the printing or other machine. My invention provides means for reducing the surface speed of the pull-out and registering rollers to avoid 10 too great impact of the blanks against the registering stops of the printing machine when it is being operated at high speed.

A further object is to provide finely adjustable means for straightening out the blank and for 15 changing lateral position of the blank without stopping the machine.

A further object is to provide means for changing lateral positioning of the blank without changing or disturbing adjustments already made 20 to secure accurate register.

A further object is to provide convenient and simple means for cutting off the conveyor or registering unit. This is a convenience, as the load is taken off the multigraph and it may be more 25 easily turned by hand as is necessary in preparing the type, ribbon, etc., for each job to be printed.

A further object is to provide a light-running delivery or registering unit through a simple arrangement of pull-out and angle rollers, belts, belt tighteners, etc.

A further object is to provide simple means for adjusting the angle roller driving belt against the angle rollers to secure positive driving.

35 A further object is to provide a convenient arrangement of parts to facilitate removing and replacing of belts.

A further object is to provide a short angle roller near the delivery end of my conveyor adapted to register short blanks, simple means 40 of mounting this roller, and simple and self-adjusting means of driving this short roller.

A further object is to combine in a compact 45 removable pull-out and registering unit, pull-out rollers, angle rollers, means for driving them from a driven pulley which is a part of this unit, adjustable means for aligning the blank being registered, means for weighting the blank, and means of adjusting the entire pull-out and registering unit laterally, said adjusting means being adapted to co-operate with means upon the supporting structure provided.

A further object of my invention is to provide a 55 convenient arrangement of guides, balls, ball holders and other auxiliary means in conjunction with the rollers to deliver the blank, speedily, positively and exactly into the desired position and to hold it there until acted upon by the printing or other machine.

60 A further object is to provide a hand feed pan to be mounted upon the slidable conveyor, and means for rendering the feeding and conveyor driving means inoperative so that when the operator wishes to feed by hand, he may do so without driving the automatic feed or any part of it.

A further object is to combine in a channel-shaped ball-holding guide through which idler balls may project so as to bear upon blank delivering means, a plurality of ball retaining pieces 70 adapted to slide in said channel-shaped guide, and self-acting means of locking said ball retaining pieces in position over holes in the bottom of said channel-shaped guide.

A further object is to provide a convenient 75 mounting for a wiping pad so that it may be eas-

ily placed in operative position against the feeding roller or in idle position, as desired.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

5 For a clearer comprehension of the operation of this invention, it is herein shown in connection with the multigraph and power drive commonly used with the multigraph.

10 In the accompanying drawings which are to be taken as a part of this specification, and in which I have shown merely a preferred form of embodiment of the invention:

15 Fig. 1 is a perspective view of the right side of my automatic feed as used with the multigraph, its power drive base and stand, which are shown in part.

20 Fig. 2 is a perspective view of the left side of the equipment shown in Fig. 1.

25 Fig. 3 is a perspective view of the roller conveyor or register board of my feeder removed and inverted.

30 Fig. 4 is a side elevation of magazine and separator with some parts broken away to show construction details.

35 Fig. 5 is a fragmentary sectional view taken longitudinally and vertically through the magazine and its supporting frame.

40 Fig. 6 is a section taken through plane 6—6 of Fig. 4.

45 Fig. 7 is a fragmentary plan view of feeder with ball holders and guides removed and roller driving parts omitted.

50 Fig. 8 is a fragmentary vertical section taken through the conveyor in a plane at right angles to the conveying rollers and to the right of the roller driving mechanism which is shown in this view.

55 Figs. 9 and 10 are respectively diagrammatic plan and elevational views illustrating arrangement of gears, belts, pulleys, etc. in the assembly of multigraph, power drive base, and motor with my feeder and conveyor.

60 Fig. 11 is a sectional elevation taken at 11—11 of Fig. 7, on a larger scale.

65 Fig. 12 is a plan view of one of my ball holding guides, on a larger scale than Fig. 24.

70 Fig. 13 is a section taken in the vertical plane 13—13 of Fig. 12.

75 Fig. 14 is a vertical section taken in the plane 14—14 of Fig. 12, on a larger scale.

80 Fig. 15 is a side elevation of one of the ball holding blocks shown in section in Fig. 13.

85 Fig. 16 is a transverse vertical section taken through one of the ball holding blocks.

90 Fig. 17 is a bottom view of the block shown in Fig. 15.

95 Fig. 18 is a plan sectional view showing details of conveyor roller construction and mounting.

100 Fig. 19 is a vertical section taken at 19—19 of Fig. 12 on a larger scale.

105 Fig. 20 is a side elevational detail of conveyor with hand feed pan attached.

110 Fig. 21 is a section taken through the plane 21—21 of Fig. 20.

115 Fig. 22 is a plan view of hand feed pan re-70 moved from conveyor.

120 Fig. 23 is a right side elevation of the left guide of my registering conveyor indicating the flexible retainers in position against the edge of a blank being registered.

Fig. 24 is a plan view of part of conveyor with blank in position as registered against stop fingers of the multigraph.

Fig. 25 is a sectional plan view of feeding roller shaft and ratchet mechanism.

Fig. 26 is a plan sectional detail of main drive shaft and bearing of the roller conveyor.

Figs. 27 and 28 are respectively plan and elevational details of my conveyor showing different construction from that of previous figures, and particularly a short roller and the means I employ to drive it.

Fig. 29 is a bottom view of the short roller and plate upon which it is mounted, removed from conveyor.

Figs. 30, 31, 32, 33 and 34 relate to a different arrangement of parts from that shown in Fig. 11 and other previous figures, Fig. 30 being a sectional elevation taken through the frame of the feeder with conveyor removed looking towards the magazine which is not shown in this view.

Fig. 31 is a plan view of the assembly as shown in Fig. 30.

Figs. 32, 33, and 34 are sectional elevations viewed from the right side of the feeder showing different arrangements of parts for different kinds of blanks.

Figs. 35 and 36 are respectively right and left elevational details of a ratchet cut-off which I provide with the construction shown in Figs. 30, 31, 32, 33, and 34.

Fig. 37 is a section taken at 37—37, Fig. 8.

Fig. 38 is a plan view of the mechanism shown in Fig. 36, with mounting and stroke regulating device added in section.

Fig. 39 is a transverse section of the right guide as shown in Figs. 7 and 24.

Fig. 40 is a plan view of the stroke regulating collar.

Fig. 41 is a view taken at 41—41 of Fig. 38 showing the action of the pawl in connection with the stroke regulating collar.

Fig. 42 is an elevation taken at 42—42 of Fig. 30 showing mounting of the feed belt brackets.

Fig. 43 is a diagrammatic elevational detail showing operation of the belt tightener releasing and locking mechanism used to cut-off the conveyor.

Fig. 44 is a plan view detail of the mechanism shown in Fig. 43.

In the perspective views Figs. 1 and 2 my feeder is shown attached to the power drive base 1 regularly used upon the tubular stand 2 to support and drive the multigraph 3. The arrangement of driving mechanism in the power drive base is substantially as shown in Gammeter's Patent No. 1,048,305, except that, instead of having the direct gear connection with the motor as shown in Fig. 6 of that patent, the motor is in more recent practice mounted upon the lower cross braces of the tubular stand, and a belt 4, driven by the motor pulley drives the pulley 5 upon the shaft 6, Figs. 9 and 10 of this application. In practice the shaft 6 is much longer than the corresponding shaft 64, Fig. 6 of the patent above referred to, so that between the bearing lugs which support this shaft there is a distance of about 9 or 10 inches. Upon this shaft and between these bearing lugs I place a multiple speed drive pulley 7 to drive my roller conveyor, using the crossed belt 8 and the large driven pulley 9 on the shaft 10 of the conveyor.

The multigraph 3 as shown is of a well known construction and may be considered, for example, as made in accordance with Patent No. 846,992.

In Figs. 9 and 10 the general arrangement of

gears used in the ordinary multigraph and power drive base is illustrated. The belt 4 is driven by the motor pulley. It drives the large pulley 5 which is pinned to the shaft 6. On the end of this shaft is a small gear 11 which drives the intermediate gear 12, which in turn drives the platen gear 13, which meshes with the large gear 14 of the printing member. The intermediate gear 12 has mounted upon the same shaft with it a small gear 15 which drives the crank 16 by 10 engaging the gear 17 mounted on the same shaft with the crank. The crank makes one revolution with each revolution of the printing drum.

As illustrated in Fig. 1, I use the crank 16 to make the feed stroke and to time the feed stroke 15 so that the blank will be delivered to the multigraph when its paper fingers or registering stops are in their upper position. To time the feed stroke the set screw 18 is loosened and the arm 16 is turned upon its shaft 19 to the desired position and locked by tightening the screw 18. The link 20 is notched to fit over the shoulder screw 21 carried by the crank arm 16.

The supporting frame 22 of my feeder has a plate 23, Figs. 7 and 20, with holes to match the tapped holes in the power drive base 1, which are provided for mounting other types of feeding devices such as the ones described in Patents Nos. 1,052,332, 1,051,726 and 1,457,158. The two screws 24, Figs. 7 and 20, aside from the belt 8 and the link 20, are the only connection my feeder has with the power drive base. Since there is no connection of my feeder with the multigraph itself, the latter may be removed from its base for cleaning, adjusting, etc., entirely independent 35 of the feeder.

When it is desired to disconnect the feeder entirely, all that need be done is to remove link 20, throw the belt 8 off the conveyor pulley 9 and remove the two screws 24. The conveyor itself may be removed as in Fig. 3 to admit better access to the screws 24. This convenient knock-down construction as hereinafter more fully described is an important feature of my invention.

Having thus briefly described how my feeder 45 may be attached to and driven by the power drive base commonly used with the multigraph, I will now describe the construction and operation of the feeder itself.

The stand is made up of four upright members 50 25 of equal length, 2 upper and 2 lower longitudinal braces 26, 2 front and 2 rear cross braces 27. The frame 22 rests upon the upper longitudinal braces 26, being held there by the upper ends of the uprights 25 as shown at 28, Fig. 2. 55 The base frame 22 is made up of left and right longitudinal side members 29, a rear cross piece 30, a centre cross piece 31, and a front metal structure composed of angles 32 to which are attached by screws or other suitable means, slide 60 members 33 and 34 and an attaching plate 23 riveted to the slide member 33. A rear slide plate 34A strengthens the frame structure. A cross rod 35 is provided, its ends being let in the side members 29. Attached to the cross member 31, Fig. 4, is a plate 36 having tapped holes to receive T-screws 37 by means of which the base of the magazine and separating unit is mounted upon the base frame 22.

The base of the magazine and separating unit 70 is made up of a right side member 38, Fig. 4, and a left side member 39, Fig. 2, and a brace member 40, shown in section in Fig. 11, to which the side members 38 and 39 are attached by means of screws 41. The side members are provided 75

with holes to receive T-screws 37 for mounting upon the centre cross piece 31 of the frame 22. These screws 41 also hold left and right plates 42 in place. Near the upper ends of these plates the U-shaped frame 43 is pivoted upon the cross rod 44. The frame 43 is held rigid by the sheet metal plate 45 bent around the cross rods 46 which are riveted in place. U-shaped piece 47, having notches to fit the cross rod 35, and pivoted 5 at 48 on the frame 43 provides a means of adjusting the magazine pan to any desired angle. Springs 49 hold the U-shaped frame firmly in place once it is set. Safety stops 50 are provided to prevent the springs 49 from being broken by 10 accidental dropping of the magazine supporting structure.

The magazine pan is made up of 2 sheet metal pieces bent at right angles longitudinally. The right side 51 is removably attached to the cross rod 52 of the frame structure 43, by means of 15 spring clips 53, which are riveted to it. By this means the magazine pan is movable sidewise by sliding along the rod 52, and it is removable by forcing up off the rod. To attach the pan the clips 53 are forced down over the rod 52. The bracket 55 bolted to the right side of the magazine pan holds the end of the adjusting rod 56 which is screwed into it. A sliding bracket 57, fitted with a thumb screw 58 holds the left side 54 to 20 which it is bolted, in any desired position along the rod 56. The left side 54 is narrow so that when closed up against the right side 51 a lift of narrow blanks will be accommodated. When open wide the magazine is wide enough to take a maximum width blank while there is plenty 25 of room for lateral adjustment to suit the lateral position of the type of the printing form; for instance, for a blank of two-thirds maximum width to be run at the extreme left side of the printing drum, the pan may be set for size by closing the side 54 into correct position along the rod 56, then for correct lateral position with regard to the matter on the printing drum, by sliding the 30 entire magazine pan to the left along the rod 52. The blanks are fanned and loaded into the 35 magazine pan as shown in Figs. 1 and 2. The rubber feed roller 59 which is supported and rotated intermittently in a counter-clockwise direction by mechanism to be described, is shown in Figs. 4 and 11 in position relative to the magazine and the adjustable separator. The uppermost of the lift of blanks fed downwardly by gravity, is the first to come in contact with the rubber feed roller 59. As the feed roller is rotated the blank is fed forward, the second blank is also moved forward slightly by the friction of the first against it. But the resistance 40 which the second blank encounters when it comes against the separating rubber 60 is greater than the friction between the first and second blanks, so the second is stopped and is not fed until the first is out of the way and the friction roller comes in direct contact with it.

The separator rubber 60 is a short length of 45 ordinary commercial rubber tubing shaped as indicated and forced on the adjustable separator finger 61, having an enlarged rear portion bored to fit upon the tube 62 upon which it may be moved laterally to any desired position and fixed 50 by the thumb screw 63. The tube 62 is held in place by the rod 64 which is threaded at one end and screwed into the left plate 42; it is bent at the other end to form a convenient lever for unscrewing when it is desirable to remove the separator finger and renew the rubber 60.

To adjust the separator towards and from the feed roller a plate 65 pivoted at its rear edge in the plates 42 is provided. The front edge of this plate 65 bears against the separator finger and is adjustable by the thumb screw 66 with lock 5 nut. Guides 67 are removably supported by the rod 44.

The rubber feed roller 59 has a metal hub 68 fitted with set screw 69 so that it may be fixed tight upon the shaft 70 in any desired position. 10 The separator finger is moved along the tube 62 and locked in position underneath the feed roller, and is adjustable to and from the feed roller, in any lateral position by the plate 65 and the screw 66.

The shaft 70 is bored at its left end to fit over the bearing pin 71, Fig. 25 which is removably mounted in the left side member 39. A set screw 72 holds the bearing pin 71 in place. The right end of the shaft 70 is bored and notched to fit 20 over the hub of and be rotated by the pawl wheel 73 through the pins 80 fixed therein. This pawl wheel is rotated intermittently by the crank 16 of the power drive base through the link 20 and its associated parts. The upper end of the link 25 20 is slotted and has a rack 74 mounted upon the lower side of the slot so that it meshes with the gear 75 pinned to the shaft 76. A collar 77 pinned to the shaft 76, and a roller 78 hold the link and rack in alignment. The shaft 76 is journaled 30 in the right side member 38 of the feed unit base. The screw 79 holds the pawl wheel 73 on the end of the shaft 76, upon which except for the pawls 82, it is free to turn. Mounted on one side of the pawl wheel 73 are pawls 82. Springs 83 hold 35 these pawls down against the ratchet wheel 84 which is fixed upon the shaft 76 and is turned back and forth first in one direction and then in the other by the forward and backward motion of the rack 74 acting upon the gear 75. The motion imparted to the feed roller through this mechanism is therefore, as viewed in Figs. 4 and 11, an intermittent counter-clockwise rotation.

The parts of this mechanism are so proportioned that with one revolution of the printing 45 drum of the multigraph a blank is fed from the magazine sufficiently far forward to be engaged by the continuously rotating pull-out rollers 85 and 86 of the conveyor. These rollers complete the operation of withdrawing the blank from 50 the magazine.

The magazine and separating unit as illustrated in Figs. 4 and 11 could be mounted directly upon the power drive base 1 of the multigraph, other means of mounting the rod 35 55 being provided and a link 20 of suitable length being used.

Other types of feeders such as those illustrated in Patents No. 1,052,332, 1,051,726 and 1,457,158 may be mounted upon the cross member 31 of 60 my base frame 22 and operated from the crank 16 of the multigraph power drive base by using a longer link such as the one 20 used to operate the particular type of feeder herein illustrated and described. When so mounted and 65 used with my conveyor these feeders are no longer required to register the blank, and the feed rollers of the multigraph itself are not required to complete the operation of withdrawing the blank from the magazine. Both these functions 70 are taken over by my conveyor, and performed by it more accurately and at greater speeds than is possible when these feeders are mounted directly upon the base of the multigraph as contemplated by these patents.

It is also contemplated in this invention that means of withdrawing and registering the blanks to be fed, other than and interchangeable with, the conveyor shown herein may be used.

5 The various parts of the roller conveyor are assembled upon a frame made up of a left side member 87 and a right side member 88, Fig. 3, held parallel and a suitable distance apart by a front tie plate 89, and a rear tie plate 90. These tie plates are attached by screws to the side members as indicated in Fig. 3. As shown in Figs. 1 and 20 the front tie plate fits in the way formed by the slide members 33 and 34 of the base frame. A rack 91 attached to the slide member 33 is engaged by the pinion rod 92, the upper end of which is fixed in the handwheel 93. A thumb screw 94 fitted in the bracket 95A is used to tighten against the pinion rod thus locking the conveyor in place after lateral positioning by 15 turning the handwheel 93. The rear tie plate 90 slides upon the rear slide member 34A of the base frame.

Assembled with the conveyor frame are a series of rollers 95 at an angle as shown in Fig. 7. 25 These rollers carry the blank forward and against the right guide 96 formed of a single piece of sheet metal having channel shaped cross section as indicated in Fig. 39. As shown in Fig. 18, the rollers 95 are made of tubing and have oilless 30 bearings 97 forced into their ends. Thrust collars 98 drive fit upon the shafts 99 and prevent endwise movement of the rollers. The shafts 99 are let in the side members 88 and 87 as indicated in Fig. 18.

35 The lower pull-out roller 86 is fixed upon its shaft by means of screw 100 which may be removed when it is necessary to take out this roller to renew the rubber 101, which is provided to give it better grip on the blank 102 being pulled out from between the feed roller 59 and the separator rubber 60.

The right guide 96 is notched as shown in Fig. 7 to receive the ends of the rollers 95, and the projections 103 are bent down so as to prevent the blank from getting under them. The guide 96 is pivoted at 104 upon the angle piece 105 to which it is attached by means of a suitable countersunk rivet or screw. The guide 96 is adjustable by means of thumb nut 106 upon screw 107. The angle piece 108 is joined by pivotal connection at 109 to the guide 96. A compression spring 110, Fig. 3, pressing against the downwardly bent portion 111 of the angle piece 108, which has a hole to receive the screw 107, keeps 55 the rear end of the guide 95 as far to the right as the nut 106 on the screw 107 will permit. The pressure of this spring also tends to keep the nut locked in place after the guide has been set.

60 The rear end of the guide is partly cut away and opened as shown at 112, Fig. 4, so as to better receive the leading edge of the blank.

The cross rod 113 reduced at either end to fit into the slots at the top of the plates 114 and 65 115, is locked in place by means of wing nuts 116 and 117. This cross rod 13 supports the arm 118. The spring 119 has one end looped over the arm at 120, the other end looped around the thumb screw 121 which is fitted through the 70 collar 122. By this arrangement the desired pressure of the upper pull-out roller 85 against the lower roller 86 may be obtained. The upper pull-out roller turns upon the shaft 123 which is fixed at one end in the arm 118. The shaft 75 123 also supports the bracket 124 which carries

a felt wiper 125 used to keep the feed roller 59 clean or for applying glycerine, etc., to the roller 59 to give it better pick-up. When desired this wiper may be tilted over away from the pick-up roller 59. It will then rest against the arm 118, in idle position as shown in Figs. 1 and 2.

5 In order to keep the blank under positive control after it has passed between the pull-out rollers 85 and 86, I employ one or more ball containing guides 126 and a left guide 127, which 10 will hereinafter be described in detail.

The guides 126 and 127 are clamped by means of thumb screws to the cross bar 128, slotted as at 129 at both ends so as to be removably clamped by wing nuts and screws to the brackets 130 and 15 131 which are fastened by means of screws to the side members 87 and 88.

The ball containing guides 126 are made of sheet metal formed as shown in Fig. 19. The guides 126 are fastened to a clamp member 132 20 by means of screw 133 and plate 134, the turned-in edges of the guide 126 being held firmly between clamp member 132 and plate 134, by the screw 133. The surface 135 of the clamp 132 is tightened up against the under side of the 25 cross bar 128 by means of the thumb screw 136, supporting the guide the proper distance above the rollers 95. The rear end of the guide 126 is partly cut away as shown at 137, the bottom part is bent up as indicated, to receive the 30 leading edge of the fed blank.

I use steel balls 138 to give the rollers a more positive action upon the blank being fed. These 35 balls are held in place bearing upon the rollers if desired or in idle storage position as at 139, Fig. 13. Holes 140 are provided in the guide 126, through which the balls may project far enough to bear and turn freely on the rollers 95. The edges of the holes are bent up as shown at 141 to prevent the blank being fed from getting caught, as will frequently happen if the metal is flat at these points. The retaining blocks 142

are cut out at the bottom as shown at 143 so as to pass over the raised portions 141 of the channel formed by the sheet metal 126. The retaining 40 blocks are held in position over the holes 140 by the ball 144 and compression spring 145 arrangement as shown in the section Fig. 14. The spring 145 and the ball 144 fit freely in the hole 146 of the retaining block 142, Fig. 15, and the spring 45 being under tension keeps the ball 144 in the pocket 147 formed in the side of the channel 126, locking the retaining block in correct position against displacement by vibration or by the action of the idler balls 138 as the blanks are being 50 fed under them. While this is a very effective means of keeping the retaining blocks from creeping as the blanks are fed, it is also a very convenient arrangement, since, when desirable the retaining blocks may be easily moved by applying pressure by hand. When the retaining 55 blocks are thus forced in either direction along the channel, as the ball 144 is forced away from the pocket 147, the spring 145 is placed under greater tension. When the retaining block is 60 forced towards the pocket the locking ball 144 snaps into place locking the retaining block against displacement. If the ball 138 is to be placed in idle position as at 139, the pressure of the ball 144 against the flat wall of the channel 65 70 is sufficient to hold the retaining block and idler ball 138 in idle position.

The holes 140 in the sheet metal channel are not large enough to permit the ball 138 to pass through entirely. The hole in the retaining block 75

is small enough at the top 148 to prevent the ball 138 from passing through. The hole in the lower part 149 is large enough to allow the ball free movement for its purpose.

5 At 150 a ball is shown projecting downwardly through a hole placed between two rollers 95. At the point 151 the metal of the channel is bent downwardly to guide the blank under this ball.

10 The means used to drive the pull-out roller 86, and the angle rollers 95 is shown in Figs. 3, 8, 27, and 28. On the shaft 10, I mount in addition to the driven pulley 9, a pulley 151A for driving the belt 152 which in turn passes over a series of 15 small idler pulleys 153 placed as shown in Figs. 8 and 28 so as to cause the belt to bear against the angle rollers and rotate them. These idlers are mounted by means of shoulder screws 154 upon a plate 155; this plate is attached to the supporting member 156 by means of screws 157 which pass through slots 158 in this member.

15 As shown in Fig. 3 the supporting member 156 is mounted by screws upon the tie pieces 89 and 90. Upon plate 155 I provide pivotally mounted 20 at 159 a tightener arm 160 and a tightener pulley 161. Tension on the belt 152 is maintained by a pull spring 162 fastened at one end to the member 156 at 163 and at the other end to the pin 164 which is riveted in the arm 160. By the slot 25 arrangement shown in Fig. 37 the entire pulley and plate assembly may be adjusted up or down to obtain proper bearing of the belt 152 against the rollers 95 to drive them. To provide a supporting bracket for the shaft 10 under my conveyor and at the same time a support for the cross rod 113, I use a single strip of metal bent to U-shape. The longer leg 165 of this strip is screwed to the conveyor side 87, Fig. 2. The other leg 166 is turned under at 167 and riveted to the 30 plate 168 which is bolted to the member 156. In Fig. 26 I show how the shaft 10 is mounted in the bracket formed by this U-shaped piece. The sides 164 and 167 of this piece are bored to receive the tubing 169 which is riveted at the ends 45 170 as indicated. Oilless bearings 171 are provided for the shaft 10 to rotate in.

40 For the long belt 8 which is driven by the multigraph base I provide a tightener pulley 172 which is free to rotate upon and position itself along the shaft 173 according to the requirements of the belt 8 which may or may not be in line with the pulleys 7 and 9. The shaft 173 is fixed in the U-shaped bracket 174. This bracket 174 is pivoted on the tie rod 175, a pull spring 176 fastened 50 to one leg of the bracket 174 being provided to maintain the tension on the belt 8 through the idler pulley 172.

55 The pulley 176A mounted on the end of the shaft 10 drives through the crossed belt 177 the pulley 178 on the shaft of pull-out roller 86. To keep this belt 177 taut I provide an idler pulley 179 mounted upon an arm 180. This arm 180 is pivotally mounted near its lower end upon the bracket 165. Spring 181 attached at one end to the side member 87 and at the other to the upper end of the arm 180 maintains the tension on the crossed belt 177. The idler pulley 179 is out of line with the pulleys 176A and 178 so as to hold the belt 177 clear of itself where it crosses. 60

70 In Figures 23 and 24, as well as in Fig. 1, I show flexible members 181A mounted on the left guide 127. The purpose of these members is to retain the blank in alignment after it has been delivered against the stops.

75 In practice the left guide, 127, is set slightly

further to the right than is shown in Fig. 24. The action of the angle rollers and balls upon the blank 182 causes the blank 182 to be brought against the guide 96 as soon as it is released from between the pull-out rollers. The blank then comes against the inside surface of the lower portion of the flexible members 182, bending them outward slightly. The spring tension on these pieces 181A is not great enough to prevent the free movement of the blank. However, it is sufficient to prevent the blank from rebounding out alignment when it strikes the stops 183 of the multigraph.

184 and 185 indicate, respectively, front and rear filler plates. These filler plates are screwed, 15 as indicated, to right and left side members 87 and 88. Their edges are turned down, as indicated in section in Fig. 23. The members 181A project below the level of the top of the angle rollers, as indicated in Fig. 23, and screws 186 20 are provided so that they may be placed in different positions according to the length of the blanks being fed.

25 In Fig. 24 I show a blank in position against the stop fingers 183, a single ball 150 on the blank being between the rollers, as shown also in Fig. 13. The other balls and ball retainers over the blank in this position have been omitted from Fig. 24 for the sake of clearness. I have found by experience that this single ball between 30 these rollers as shown, and resting on the blank in registering position, together with the flexible members 181A properly set will give splendid registration.

35 When it is desirable to have heavier idlers on the blank as is advantageous in feeding envelopes and heavy card stock, I use steel balls of larger diameter. These may be used in the same channel guide as the smaller ones. To accommodate the larger balls I use a retaining block 40 such as is shown in Figs. 16 and 17, etc., except the hole 149 is bored larger and entirely through the block one size, the upper turned in edges of the channel serving to prevent the ball from being removable through the top of the channel. 45

50 In order to mount the hand feed pan shown in Fig. 20 the cross bar 128 with the left guide 127 and ball holding guides 126 is removed by loosening the wing nuts 187 by which it is clamped to the brackets 130 and 131, and the cross rod 133 with upper pull-out roller, etc., is removed by loosening the wing nuts 116 and 117. The rod 188 is inserted in the slots of the brackets 114 and 115 and wing nuts 189 are tightened. The pan 190 is turned up on the right edge to form 55 the right guide 191 and on the left edge 192 to form a mounting for an adjusting bracket 193. It is cut out as at 194 to permit the narrow blanks over towards the left side of the multigraph. The pan 190 is pivotally attached to the rod 188 60 by the countersunk screw 195. By the slot in the pan 190 and screw 196 the pan is adjustable for alignment. For lateral positioning the hand-wheel 93 is used the same as when feeding automatically. An adjustable left guide is formed 65 of the sheet metal piece 197 bent up as at 198. An adjusting rod 199 screwed into the bracket 200 which is bolted to the left guide 198, forms, together with the bracket 193 fitted with thumb screw 201 means of adjusting the left guide to- 70 wards and from the right guide 191.

75 Figs. 27, 28, 29, 30, 31, 32, 33, 34, 35, 36, 38, 40, 41, 42, 43 and 44 show different construction from previous figures with improved features added.

In this construction a U-shaped angle frame 75

202 is used for mounting the magazine and conveyor of improved construction.

For mounting the feeding roller, separator and associated parts, I use the bracket 203 cast in one piece, forming also the rear slide 204 corresponding with rear slide member 34A, Figs. 1, 2, and 7, for the conveyor. This bracket 203 is mounted on the sides of the angle iron frame 202 as shown, by screws 205.

While in this construction a narrow feeding roller such as is shown at 59, Figs. 1 and 7, may be used, I show in Figs. 30, 31 and 32 a wide rubber covered feeding roller 206 grooved down to the core 207 to carry a rubber feeding belt 208. The shaft 209 upon which this feed roller 206 is mounted runs free in long bushings 210 and 211. These bushings are forced into the enlarged side portions 212 and 213 of the bracket 203. End-wise movement of the shaft 209 is prevented by the collar 214 on the left end and the ratchet wheel 215, fitting tight on the right end as shown. On the inwardly extending portions of the bushings 210 and 211, the brackets 216 are mounted as shown in Figs. 30, 31, and 42. The metal is cut away as at 217 and the portions 218 closed so as to cause them to grip the bushings tight enough to hold in position and yet not too tight to be moved by hand pressure. The rod 219 mounted in the upper ends of these brackets carries the feed belt idler pulley 220 and also the guides 221 adjustable by the thumb screws 222.

The separator adjusting plate 223 is pivoted on screws 224 in the sides of bracket 203. The separator and guide holding rod 225 is similarly mounted by pivot screws 226. The separator adjusting screw 227 with lock nut 228 is fitted in the lug 229, cast integral with the bracket, this lug being an extension of one leg of the angle shaped portion 230 of the bracket 203 which forms a supporting rest for the guides 231, 232, or 233 according to the set being used for the particular kind of blanks being fed. A U-shaped frame 234, shown only in part in the drawings of this construction, corresponds with the frame 43 shown in Fig. 4. The frame 234 is pivotally mounted by shoulder screws 235 on the sides of the bracket 203. The pan 236 is of construction similar to the pan detailed in Figs. 4, 5, and 11, except that in this latter mentioned design the bottom of the pan is bent down at the point 237, Fig. 11 near its lower end. The pan 236 pivotally mounted in a manner similar to the mounting shown in Fig. 5, is equally well adapted to serve with any one of the three sets of guides and separator fingers shown in Figs. 32, 33, and 34. In changing from one set of guides to another the pan pivots about its upper supporting rod, corresponding with the rod 52, Fig. 5. In changing the angle or slope of the pan 236 it pivots substantially about its lower edge where it rests upon the guides 231, 232 or 233 and corresponding separator finger.

The separator fingers 241, 242, and 243 have reduced lower portions adapted to receive the rubber separator tubing 60. The upper edge of the separator rubber is flush with the surface of the finger and continuous with it, presenting no obstruction to the sliding of the blanks. The separator fingers have portions extending down below their corresponding guides to rest upon the separator adjusting plate 223 as shown in Figs. 32, 33, and 34.

The formation of the bracket 203 in one piece has many advantages. Among them may be mentioned, economical manufacture, rigid brac-

ing for the angle iron frame 202, permanent alignment of the bearings 210 and 211 once they are bored true. In this one piece are provided the slide 204 for the conveyor, the rest 230 for the guides 231, 232 and 233, and a mounting 5 225 for same, mounting for the separator finger adjusting plate 223, mounting for the adjusting means 227 for this plate, and bearings for the feed roller shaft: the rest 230 also serves as a bracing means for the casting itself.

As previously stated, I have found that blanks of different inherent qualities "naturally" present themselves to the feeding roller at different angles when placed in a gravity hopper such as the one I employ. Short, stiff or bulky blanks will tend to stand up as at 238, Fig. 32. Longer, less stiff, less bulky or curled-down blanks will tend to take the direction shown at 239, Fig. 33. Flexible, thin, flat or curled-up blanks tend to lie down flat as at 240, Fig. 34. In order to accomplish 10 the feeding forward of the leading blank with minimum resistance of the separator rubber 60, I use interchangeable separator fingers 241, 242, and 243 of different curvature as shown, to bring the line of tangency of the separator rubber 25 with the feed roller as nearly as possible to correspond with the direction of the leading blank of the particular kind of blanks being fed. The wide roller 206 and the guides 231, assist materially in securing uniform flexing of stiff, bulky and irregular blanks, securing proper presentation to the pull-out rollers 244 and 245.

The feed belt 208 serves a double purpose. It is made of very live rubber and presents a longer gripping surface lengthwise of the blank. When the magazine pan is nearly empty it maintains the leading blank in proper direction against the lever and fulcrum action of the following blanks at the end of the lift. The arms 221, adjustable about the rod 219 prevent too heavy packing 40 down of the blanks against the feed roller 206 and feed belt 208.

To summarize, the hopper 236 adjustable for slope, pivotally mounted to co-operate with the interchangeable guides and separator fingers; interchangeable guides and separator fingers adapted to bring the separating rubber into appropriate angular relationship with the "natural" direction of the leading blank; separator fingers of different curvature, adapted to co-operate with the common adjusting means; guides adapted to co-operate with the pivotally mounted hopper, with the separator and with a narrow or wide feed roller to secure proper presentation of blanks to the feeding roller and uniform flexing 45 and presentation to the pull-out rollers; a wide feeding roller grooved to carry a feeding belt adjustable towards and from the leading blank; and adjustable retarding member adapted to prevent the packing down of short heavy or bulky 50 blanks against the feeding roller and belt;—these several members and means, shaped, mounted and adjustable substantially as described, when used in appropriate combination, constitute simple, practical and efficient means of feeding 55 blanks of a wide variety of length, width, stiffness, thickness, curvature, etc. As is obvious from the description and drawings the set-up may be made in different lateral positions, within the range of the structure shown.

In Figures 35, 36 and 38 the link 246 corresponds with the link 20, Figs. 1 and 7, being attached to the crank 16 of the multigraph. The link 246 is bolted to the fork 247 to which the rack 248 is riveted. The rack 248 engages the 70 75

5 gear 249 forced on the hub 250 of the pawl wheel 251. The bushing 252 which fits tight in the pawl wheel runs free on the reduced shaft 209, and extends through the flanged roller 253 which runs free upon it. The hand wheel 254 fixed tight upon the further reduced end of the shaft 209 holds the assembly in place.

10 The pawl 255 is mounted on the wheel 251 by the shoulder screw 256. The pawl spring 257 15 strung between the pin 258 fitted in the pawl and the pin 259 fitted in the pawl wheel serves to keep the pawl in operative position to engage the teeth of the ratchet wheel 215 or to hold it in idle position as indicated by the dotted line, 20 Figure 36. In Figs. 38, 40 and 41 I show a special shaped collar 260 mounted upon the right end 261, Fig. 30, of the bushing 211. This collar has a thin partly cut away portion 262 extending over the ratchet wheel 215. As the arm 16 and 25 the gear 249 are of such proportions that the pawl 255 can at most travel slightly more than one-half the circumference of the ratchet 215, the length of the feed stroke imparted to the feeding roller can be conveniently regulated, by 30 turning the collar 260 about the bushing 261 and locking with the screw 263 in the desired position. As will be apparent from Fig. 41 the pawl 255 on the back stroke will be lifted away from the ratchet teeth when it comes to the edge of 35 the portion 262 of the collar 260. On the feeding stroke it cannot engage the teeth until it has dropped off this portion.

40 The cut-off provided in this pawl arrangement is useful as before explained, when it is necessary 35 to rotate the multigraph without feeding. The device just described enabling the operator to regulate the length of the feed stroke is particularly useful in the feeding of short blanks, where the feed stroke must be just long enough 40 to deliver the leading edge of the blank to the pull-out rollers.

45 In the conveyor construction shown in Figs. 27, 28, 29, 43 and 44, the left side 264, the right side 265 and the pulley supporting member 266 are 50 tied together and held in position by screws through the front and rear tie plates, 267 and 268 as indicated, forming a rigid structure. This structure is further strengthened by a cross plate 55 corresponding with the plate 128, Fig. 24, bolted to the lugs 269 and 270 cast as part of the side members; by a tie rod corresponding with the rod 113, Fig. 7, mounted between the lugs 271 and 272 cast as part of the side members 264 and 265; by the tube 273 and rod 274 brace between the lug 275 cast as part of the side 264 and the lug 276 cast as part of the pulley supporting member 266; further strengthening is furnished by the cast rear filler plate 277 screwed to suitable lugs on the sides 264 and 265 as shown, and by a 60 cast front filler plate 278, its right end let in and screwed to the right side 265, its left end carrying a lug 279 to receive the screw 281 through the left side 264, as indicated in Fig. 27. Rollers 95 of the same design and mounting as shown in 65 Fig. 18 are used in this construction. The small roller 282 rotates on the shaft 283 fixed in the small lugs 284 and 285 cast on the under side of the front filler plate 278, Fig. 29. The shaft 10 with grooved pulleys 9, 151A and 176A fixed 70 upon it is journaled in the lugs 275 and 276.

75 The driving of the pull-out rollers, the rollers 95 and the adjustment of the plate 287 is substantially as shown in Figs. 7 and 37 except that in order to drive the small roller 282 the idler pulley 288 is mounted on an arm 289 which swivels

about its opposite end upon the shoulder pin 290 fixed in plate 287 as indicated in Figs. 27 and 28. The pull of the spring 162 on the belt 152 causes the belt to be forced up against the small roller on account of the swivel point 290 being below the center line of the pull. The parts are so proportioned that the belt around the pulley 288 just clears the base of the multigraph 291. As the roller 282 must be as near the multigraph as possible to feed short blanks and the pulley 288 10 must be as large as possible to avoid too great wear on the belt an adjusting screw 292 with lock nut is provided in the plate 267 and bearing against the bottom edge of the pulley mounting plate 287. This screw locks the plate 287 in 15 adjustment and prevents the pulley 288 from swinging too far back under the roller 282, as may happen if the plate 287 drops all the way down to the tie plate 267.

20 The U-shaped frame 174, Figs. 43 and 44, carrying the tightener pulley shaft 293 swings on the tube brace 273. The spring 176 looped around the shaft 293 and in the casting 276 as indicated maintains the tension on the belt 8. When it is desired to turn the multigraph without driving 25 the conveyor the tightener pulley 172 is lifted as in Fig. 43 by raising the handle 294 into the upper position indicated. Without the tightener pulley bearing down on the belt the driving pulley 7 under the multigraph slips about the belt 8 30 instead of driving it. The handle 294 is fixed in the arm 295 which turns about the shoulder screw 296 in the side 265. The link 297 shaped as shown at one end fits freely about the reduced part of the handle 294 and at the other fits freely 35 about the reduced part of the shaft 293 fitted with retaining nut and washer. As the handle is raised to its upper position it passes the centre line of shaft 293 and shoulder screw 296. The link strikes the screw 296 and is thus held in this 40 position by the tension of the spring 176.

Having thus shown and described my invention what I claim is:

1. In mechanism for feeding sheets to a duplicating or other machine, the combination with 45 means for feeding front portions of the sheets successively from the top of an inclined supply thereof, of a sheet handling unit comprising pull-out means for drawing the sheets forwardly in succession past the feeding means from said supply, conveying means for advancing each forwardly drawn sheet, means for guiding the sheets on the conveying means, and means for retaining the sheets in engagement with the conveying and guiding means; means for adjusting the sheet handling unit laterally of the feeding means, and means for driving said pull-out and conveying means continuously and providing for adjustment of said unit as aforesaid. 50

55 2. In sheet feeding mechanism, a normally stationary finger in substantial alignment with the blanks in the front portion of the supply and an intermittently driven feed wheel or roller frictionally cooperating therewith for feeding front portions of sheets successively from a supply thereof, one or more adjustable devices for maintaining the substantial alignment of the blanks in the front portion of the supply with the said finger, one or more devices for guiding the front portions of the sheets between the feed wheel or roller and the finger, inclined means for supporting the supply and from which said portions of the sheets are fed one after another over said device or devices between the feed wheel or roller and said finger, and continuously driven means 60

for pulling the sheets forwardly one after another through the feed wheel or roller and the finger from said supply.

3. In sheet feeding mechanism, an intermittently driven feed wheel or roller for feeding front portions of sheets successively from a supply thereof, means for supporting interchangeable fingers conforming with various angles of inclination of the front portion of the supply and for retaining one of said fingers frictionally engaged with the feed wheel or roller to cooperate therewith in feeding the front portions of the sheets as aforesaid, inclined means for supporting the supply and from which said portions of the sheets are fed one after another from the top of the supply between the feed wheel or roller and the finger cooperating therewith, and continuously driven means for pulling the sheets forwardly one after another through the feed wheel or roller and said finger from said supply.

4. In sheet feeding mechanism, a normally stationary finger and an intermittently driven feed wheel or roller frictionally cooperating therewith for feeding front portions of sheets successively from a supply thereof, an endless belt passing around and intermittently driven by the feed wheel or roller and cooperating with the same and said finger to feed the front portions of the sheets as aforesaid, inclined means for supporting the supply and from which said portions of the sheets are fed one after another from the top of the supply between the finger and said feed wheel or roller and endless belt, and continuously driven means for pulling the sheets forwardly one after another between the finger and the feed wheel or roller and endless belt from said supply.

5. In sheet feeding mechanism, inclined means for supporting a supply of sheets and on which the supply may fan out progressively from a flat position at the rear of said supply to a substantially vertical position at the front thereof, a guide for the top of the supply, a normally stationary finger and an intermittently driven feed wheel or roller moving in one direction only and frictionally cooperating with the finger for feeding lower portions of the sheets downwardly in succession from the front of the supply, continuously driven means for pulling the sheets forwardly one after another through the feed wheel or roller and said finger from said supply, and means for guiding the downwardly fed sheets to said continuously driven pulling means.

6. In sheet feeding mechanism, a normally stationary finger pointing substantially in the direction of feeding and an intermittently driven feed wheel or roller rotating in one direction only and frictionally cooperating with the finger for feeding front portions of sheets successively from a supply thereof, inclined means for supporting the supply and from which said portions of the sheets are fed one after another from the supply between the feed wheel or roller and the finger, opposed continuously driven rollers for pulling the sheets forwardly one after another through said feed wheel or roller and said finger from said supply, a wiper for the feed wheel or roller, and means for yieldably supporting one of said sheet pulling rollers and said wiper.

7. In sheet feeding mechanism, means for feeding front portions of sheets successively from a supply thereof and comprising a driven shaft and a feed wheel or roller fixed thereon, means for pulling the sheets forwardly one after another past the feed wheel or roller from said supply, a drive shaft aligned with the driven shaft in tele-

scopic relation therewith, means for oscillating the drive shaft, and connections between the drive shaft and said driven shaft for intermittently rotating the latter and said feed wheel or roller in one direction only.

8. In sheet feeding mechanism, means for feeding front portions of sheets successively from the top of an inclined supply thereof and comprising a driven shaft and a feed wheel or roller fixed thereon, means for pulling the sheets forwardly one after another past the feed wheel or roller from said supply, a rotatable member loosely mounted on the driven shaft aforesaid, means for oscillating the rotatable member, connections between said rotatable member and said driven shaft for intermittently rotating the latter and said feed wheel or roller in one direction only and means operable upon said connections for regulating the amount of or stopping the rotation of the driven shaft and feed wheel.

9. In sheet feeding mechanism, means for feeding front portions of sheets successively from a supply thereof and comprising a driven shaft and a feed wheel or roller fixed thereon, means for pulling the sheets forwardly one after another past the feed wheel or roller from said supply, a rotatable member loosely mounted on the driven shaft aforesaid, means for oscillating the rotatable member, connections between said rotatable member and the driven shaft for intermittently rotating the latter and the feed wheel or roller in one direction only, and means operable upon said connections for regulating the amount of rotation of said driven shaft and said feed wheel or roller.

10. In sheet feeding mechanism, a sheet conveyor comprising continuously driven rollers extending diagonally of the path of travel of sheets longitudinally of said conveyor, means adjacent said rollers for guiding the sheets during travel of the same one after another along the conveyor, means for feeding the sheets successively to the conveyor and comprising opposed continuously driven rollers extending transversely of said path at right angles thereto, and means for adjusting said conveyor and said feeding means transversely as a unit.

11. In sheet feeding mechanism, opposed driven rollers for feeding sheets, a guide along which the sheets are fed one after another from said rollers, a conveyor for feeding the sheets along the guide and comprising driven rollers extending diagonally of said guide and said first named rollers, one or more supports spaced from the guide laterally thereof and mounted above the driven diagonally extending rollers longitudinally of the conveyor, and rolling weights or balls carried by said support or supports and cooperating with the driven diagonally extending rollers to maintain the sheets in engagement therewith, and means of adjusting transversely all these members without changing their relation to one another.

12. In mechanism for feeding sheets to a duplicating or other machine, means for feeding front portions of the sheets successively from the top of an inclined supply thereof, pull-out means for drawing the sheets one after another forwardly past the feeding means from said supply, oscillating means for driving the feeding means intermittently in one direction only, means for continuously driving said pull-out means and means operable upon said oscillating means for stopping and starting the feeding means.

13. In sheet feeding mechanism, a normally

- stationary finger and an intermittently driven feed wheel or roller with which said finger frictionally cooperates for feeding front portions of blanks successively from a supply thereof, said finger being in substantial alignment with the blanks in the front portion of the supply, one or more devices adapted to support the lower edges of the blanks in the front portion of the supply and to guide them between the feed roller and said finger and between continuously driven pull-out means for pulling the blanks forwardly one after another through the feed wheel and the finger from said supply.
14. In sheet feeding mechanism, an inclined hopper adapted to support the lower edges of a supply of blanks therein, a finger or fingers adapted to support the lower edge of said inclined hopper and form a continuation thereof for supporting the lower edges of the blanks in the front portion of said supply, a feed roller adapted to cooperate with one of said fingers for feeding blanks one at a time from the supply.
15. In sheet feeding mechanism, an inclined hopper adapted to support the lower edges of a supply of blanks therein, means for supporting interchangeably fingers of different height and curvature corresponding with various angles of inclination of the front portion of the supply, said fingers being adapted to support the lower edge of the hopper and form a continuation thereof for supporting the edges of the blanks in the front portion of said supply, one of said fingers being adapted to frictionally cooperate with a feed wheel or roller for feeding the blanks one at a time from the front portion of the supply.
16. In sheet feeding mechanism, an inclined hopper adapted to support the lower edges of a supply of blanks therein, means for supporting interchangeably fingers of different height and curvature corresponding with various angles of inclination of the blanks in the front portion of the supply, said fingers being adapted to support the lower edge of the hopper and form a continuation thereof for supporting the edges of the blanks in the front portion of said supply, one of said fingers being adapted to frictionally cooperate with a feed wheel or roller for feeding the blanks one at a time from the front portion of the supply, and one or more of said fingers being adapted to guide the edge of the front blank of the supply after it has been advanced by the feed wheel or roller away from the edges of the other blanks in the supply.
17. In sheet feeding mechanism, an inclined hopper adapted to support the lower edges of a supply of blanks therein, means for supporting interchangeably fingers of different height and curvature corresponding with various angles of inclination of the blanks in the front portion of the supply, said fingers being adapted to support the lower edge of the hopper and form a continuation thereof for supporting the edges of the blanks in the front portion of said supply, one of said fingers being adapted to frictionally cooperate with a feed wheel or roller for feeding front portions of blanks one at a time from the front portion of the supply, pull-out rollers for withdrawing the blanks from between said finger and said feed wheel or roller, one or more of the fingers being adapted to guide the front portions of the blanks in between the pull-out rollers.
18. In sheet feeding mechanism a normally stationary finger for frictionally retarding a supply of blanks in an inclined hopper, an intermittently driven feed wheel or roller frictionally engaging the leading blank of a supply for feeding successively the front portions of the blanks from the supply, adjustable means for maintaining the front portion of the supply in substantial alignment with the finger, and continuously acting means for pulling the sheets forwardly one after another through said feed wheel or roller and said finger from said supply.
19. In sheet feeding mechanism, means for feeding front portions of sheets successively from the top of an inclined supply thereof and comprising a driven shaft and a feed wheel or roller fixed thereon, means for pulling the sheets forwardly one after another past the feed wheel or roller from said supply, a rotatable member loosely mounted on the driven shaft aforesaid, means for oscillating the rotatable member, connections between said rotatable member and said driven shaft for intermittently rotating the latter and said feed wheel or roller in one direction only, and means operable upon said connections for starting and stopping the rotation of the driven shaft.

GEORGE A. GIBSON, JR.
